CLAIM

The ornamental design for a sofa bed with storage space, as shown and described.

DESCRIPTION

FIG. 1 is a front elevational view of the sofa bed with storage space in a sofa position;

FIG. 2 is a right-side elevational view thereof;

FIG. 3 is a top elevational view thereof;

FIG. 4 is a perspective view thereof;

FIG. 5 is another perspective view thereof;

FIG. 6 is a front elevational view of the sofa bed with storage space in a pull-out position;

FIG. 7 is a right-side elevational view thereof;

FIG. 8 is a top elevational view thereof;

FIG. 9 is a perspective view thereof, revealing a storage space;

FIG. 10 is another perspective view thereof;

FIG. 11 is a front elevational view of the sofa bed with storage space in a bed position;

FIG. 12 is a right-side elevational view thereof;

FIG. 13 is a top elevational view thereof;

FIG. 14 is a perspective view thereof; and,

FIG. 15 is another perspective view thereof.

The broken lines shown in the drawings depict portions of the sofa bed with storage space that form no part of the claimed design.
